UNITED STATES PATENT OFFICE.

EDWARD J. BRANDT, OF WATERTOWN, WISCONSIN, ASSIGNOR TO BRANDT AUTOMATIC CASHIER COMPANY, OF WATERTOWN, WISCONSIN.

COIN-STORAGE TRAY AND SUPPORTING MEANS THEREFOR.

Application filed March 3, 1921. Serial No. 450,585.

To all whom it may concern:

Be it known that I, EDWARD J. BRANDT, citizen of the United States, residing at Watertown, in the county of Jefferson and 5 State of Wisconsin, have invented certain new and useful Improvements in Coin-Storage Trays and Supporting Means Therefor, of which the following is a specification, reference being had therein to the accompanying drawing.

This invention relates to coin storage trays and supporting means therefor, and while susceptible of a variety of uses, is primarily designed for use in connection with 15 money-changing devices, such as the "Brandt automatic cashier", wherein a plurality of coin tubes or chutes are provided, which must from time to time be replenished with coin, and it is the primary object of the present invention to provide a storage receptacle or tray of convenient access for use in the ready recharging or replenishing of the coin tubes or chutes with new supplies of coin, as occasion demands.

20 In carrying out the invention, it is proposed to provide a coin tray of novel construction, adapted to so position the coins of different denominations that they will be separated from one another and arranged 25 for convenient access, whereby a given series of a particular denomination may be readily removed from the tray and positioned in the appropriate coin chute of the money-changing apparatus.

30 It is further proposed by the present invention to provide, in operative association with the storage tray, novel supporting characteristics of a character to permit of the assembly of the tray directly upon the 35 money-changing apparatus, the positioning and retention of the same in an upright position on a counter or the like, or the positioning of the same in a substantially flat position, in all of which positions, the coin 40 will be maintained in position and convenient of access.

45 It is a matter of common knowledge that the average handler of coin is more or less crowded for room, and economy of space counts materially, and the present invention aims to combine economy of space with increased utility for these operators.

The various features of the invention, and novel improvements in the construction and

arrangement of parts, will be appreciated 55 from the description to follow, which, for a clear understanding of the invention, is to be considered in connection with the accompanying drawings, forming a part hereof, and wherein is disclosed, for the purpose 60 of illustration, a convenient and satisfactory embodiment of the invention.

In the drawings:—

Fig. 1 is a side view of a portion of a "Brandt" money-changing device, with the 65 improved coin tray attachment applied thereto.

Fig. 2 is an end elevation of the same.

Fig. 3 is a side elevation of the tray in 70 an upright position.

Fig. 4 is a vertical sectional view of the same.

Fig. 5 is a top plan of the tray.

Fig. 6 is a top plan of the tray in flat 75 position.

Fig. 7 is a side view of the same.

With more particular reference to the drawings, wherein like reference numerals refer to corresponding parts throughout the several views, 1 is a backplate for a coin 80 tray, the same being adapted to fit in grooved portions 2 in the inner surface of sides 3 intermediate the opposite edges thereof. It will be observed that the groove 2 in one of the sides 3 is arranged nearer the 85 rear edge of this side than the groove 2 of the opposite side 3, whereby the backplate 1 will assume a lateral inclination, for a purpose to be described.

Projecting forwardly from the backplate and extending from top 90 to bottom thereof, are a plurality of partition plates 4 separated from one another, gradually increasing in distances from one side of the tray to the other, whereby to provide channels accommodating coins of 95 different sizes. The said channels are in turn divided into a plurality of separate chambers by transverse partitions or shelves 5 spaced from one another as desired, so as to take care of any predetermined number of 100 coins of the particular denomination in any particular channel. These shelves 5 are arranged at a slight inclination from their point of connection with the backplate 1 towards the forward edge of the shelves, which 105 said forward edge of the shelves preferably terminates at a point below the exposed edge of the partition plates 4, and has a

curved cut-out finger opening as indicated at 6. It is understood, of course, that the shelves gradually increase in size according to the increase in the size of the channels provided by the partitions 4, but because of the inclination of the backplate 1 with respect to the sides 2, the coins when in position on the shelves in the channels of the tray will present the exposed edges thereof in substantial alignment throughout the tray.

The sides 3 adjacent what may be termed the upper ends thereof, have rearward extensions or lugs 7 with inward offset terminals or stop members 8, whereas said sides at the opposite or lower end have relatively short rearward extensions or lugs 9.

It will thus be seen that if the tray is positioned in what may be termed the "flat position," with the lugs 7 and 9 resting upon the desk or suitable surface, the relatively long extensions 7 will position the upper end of the tray at an elevation with respect to the lower end, thereby maintaining the coins in position against the lower or supporting shelves and tending to prevent any upsetting of the same, assuming that the spaces in the channels between the shelves are not entirely filled with coins. Provision is made for supporting the tray in what may be termed an upright position, though at a slight inclination rearwardly from bottom to top, and to this end suitable legs or standards 10 are provided, the same being pivotally connected at the top to the lugs 7 as at 11 by any suitable means permitting attachment of the legs at will. The legs 10 are connected to one another by a cross brace 12, the offset terminals 13 of which are secured as by screws 14 to said legs. The legs are adapted to swing from a collapsed position in contact with stop members 14^a of the lugs 9 outwardly to a point in contact with the offset stop members 8 of the lugs 7, and in order to retain the legs 10 in either the collapsed or extended position, suitable spring bars 15 are secured at one end, conveniently on the leg-supporting spindles 11, said spring bars terminating at their free end in opposite rounded stops 16 projecting through apertures in the lugs 7 and adapted to be engaged by the legs 10 in the swinging movement of the latter and forced outwardly, thereby releasing the legs, but adapted when the legs are either in collapsed or extended position to overlie the adjacent side of the legs and retain the same in the desired position.

A suitable means for supporting the tray in upright position, on the framework or casing of the money changer, while permitting of the removal of said supporting means from the money changer, as well as the tray, comprises the following parts:

65 Arranged upon the rear surface of the

coin tray are retaining means, conveniently taking the form of substantially U-shaped loops, one adjacent each side of the rear surface of the tray, as indicated at 17, said loops being struck up from a strip of metal and one of the arms thereof being offset laterally for connection as by screws or rivets 18 to the rear wall of the tray. Opposed end supports 19 are provided, the same being secured to one another by connecting bars 20 and 20^a, the end supports being separated from one another a sufficient distance to overlie the side walls 21 of the casing of the money changer, the said end supports having arms or feet 22 and 23, respectively, having offset terminals 22^a and 23^a, respectively, adapted to engage over the upper edge of the side wall 21 of the money changer casing and the edge of the rear wall of the money changer casing, respectively. The end supports 19 have suitable thumb screws projecting therethrough and adapted to engage threaded apertures in the side walls of the money changer casing. Upright arm supports 24 are provided, the same having feet portions 25 and 26, respectively, the one 25 being adapted to be sleeved upon the connecting bar 20 and the other upon the connecting bar 20^a interposed between the end supports 19. The upright arm supports 24 have each a forwardly extending lug 25^a whereby to support the lower end of the casing, a recess being provided at the point of connection between the lugs 25 and arms 24 as illustrated at 26^a whereby to receive the lower edge of the back wall 1 of the tray. Also projecting between the upright arms is a supporting bar 27 spaced from the upper free terminals of the upright arms, which latter are adapted to loosely engage in the loop-retaining means 17 on the rear surface of the tray, when the latter is in position with its lower edge resting on the lug supports 25.

From the description it will be observed that when the tray is positioned upon the casing or framework of the money changer, a convenient auxiliary supply or storage of coins is within ready access of the operator of the changer, thereby resulting in the saving of time, labor, etc., in replenishing the coin tubes of the money changer, the trays being open, making it possible for the operator to grasp the particular amount of the particular character of coin desired with the thumb and forefinger and the particular inclination of the coin shelves of the tray retaining the latter in position. Should it be desirable to use the tray independently of attachment to the money changer casing, the tray may be readily removed from the supporting arms 24 of the support interposed between the money changer and tray, when upon extending

the legs 10 of the tray, the latter may be placed upon a counter, desk, or the like, in an upright inclined position. Then again, assuming that the day's work is over, 5 and it is desirable to store the tray in the vault, the leg supports 10 of the tray are collapsed into a position substantially flat against the rear wall of the tray, when the tray may be placed in a horizontal position, 10 and in this event also the tray will assume a slight inclination, thereby assisting in the retention of the coins in proper position in the channels of the tray, while rendering the coins ready of access and removal at 15 will when the tray is in this position.

What I claim as new and desire to secure by Letters Patent of the United States, is:

1. A storage tray for coins, having means for attachment to money changers, said tray 20 having a plurality of coin channels varying in size to correspond with the varying size of the coin channels of the money changers, said channels of the tray being divided by transverse partitions, and said channels and 25 partitions varying in sizes to accommodate coins of different denominations, and constructed and arranged whereby the exposed edges of all the coins will be maintained in substantially the same plane.

30 2. A coin tray comprising a backplate and a plurality of relatively extending partition members forming coin channels on the upper surface of said backplate, and means for supporting the plate at a transverse inclination to its supporting surface.

35 3. A coin tray comprising sides, a backplate arranged between and connected to the sides, said back plate being positioned at a lateral inclination, and shelves secured to one face of the back plate.

40 4. In combination with a coin tray, comprising a bed or plate having a plurality of coin channels, movable supporting means for maintaining the plate in upright position, said supporting means being adapted to assume a collapsed position in contact with the bed or plate, said bed or plate having retaining means secured thereto, and a removable attaching device adapted to engage 45 said retaining means whereby to mount the tray upon the frame of a money-changing device.

55 5. In combination with a money-changing device having a main frame and a coin storage tray adapted to receive a series of auxiliary coins whereby to replenish the usual coin chutes of the device, said tray having retaining means thereon, and a support to detachably engage the device, said support 60 having upwardly-extending arms to detach-

ably engage said retaining means on the tray.

6. In combination with a money changer, arms extending therefrom, and a tray carried by the arms, said tray having eye members through which the arms extend. 65

7. In combination with a money changer, arms extending upwardly therefrom, substantially horizontal projections extending from the arms, and a tray adapted to be 70 supported on the projections.

8. In combination with a money changer, arms extending therefrom, substantially horizontal projections extending from the arms adjacent their lower ends, and a tray 75 supported on the projections with the arms engaging the rear surface thereof.

9. A storage tray for coins, having means for attachment to a money changer, lugs extending from the tray and having openings therein, legs pivotally connected to the lugs, spring arms connected to the tray, and 80 projections on the spring arms, said projections extending through the openings in the lugs and engaging the legs to hold them in folded or extended position. 85

10. In combination with a money changer, supporting plates adapted to engage the sides of the money changer, means for connecting the supporting plates, arms carried by the connecting means, and a tray adapted to be supported by the arms. 90

11. In combination with a money changer, supporting plates adapted to engage the 95 money changer, transversely extending rods connecting the supporting plates, arms carried by the rods, and a tray adapted to be supported by the arms.

12. In combination with a money changer, supporting plates, rods for connecting the supporting plates, means carried by the rods for adjusting the plates to bring them in engagement with the money changer, arms carried by the rods, and a tray adapted 100 to be supported by the arms. 105

13. A coin tray comprising sides, having vertically extending grooves in their inner faces, the groove in one of the sides being arranged nearer the rear edge thereof than the groove in the opposite side, a back plate arranged between the sides, with its vertical edges received in the grooves thereof whereby the plate is positioned at a lateral inclination, and shelves secured to one face of 110 the back plate. 115

In testimony whereof I have hereunto affixed my signature.

EDWARD J. BRANDT.
